(57) **CLAIM**

I claim the ornamental design for a transparent lateral vision panel for a football helmet, as shown and described.

DESCRIPTION

FIG. 1 is a right side elevation view of a transparent lateral vision panel for a football helmet showing my new design; FIG. 2 is a left side elevation view thereof; and, FIG. 3 is a right side front angle view thereof, the opposite side view being identical thereto.

The dotted lines shown in the figure drawings are for illustrative purposes only and form no part of the claimed design.
